UNITED STATES PATENT OFFICE.

JOHN A. THOMPSON, OF AVERY, IOWA, ASSIGNOR TO DANIEL O'DONNELL AND GEORGE P. HIPPEE, JOINTLY, BOTH OF DES MOINES, IOWA.

VAPORIZER.

1,231,811.

Specification of Letters Patent.

Patented July 3, 1917.

Application filed January 21, 1915. Serial No. 3,641.

To all whom it may concern:

Be it known that I, JOHN A. THOMPSON, a citizen of the United States, residing at Avery, in the county of Monroe and State 5 of Iowa, have invented a new and useful Vaporizer, of which the following is a specification.

My invention relates to vaporizers for internal combustion engines, of the type 10 adapted to heat fuel supplied to the engine.

The object of my invention is to provide a vaporizer of comparatively simple, durable and inexpensive construction, adapted to be mounted in a manifold, or in the path 15 of fuel supply to the cylinders, and adapted both to supply fuel and to heat said fuel within the manifold or other part of the machine through which the fuel travels.

A further object is to provide such a device 20 having means whereby the fuel supply passage may be simultaneously opened to admit fuel, and the source of heat connected up for heating fuel supplied through said passage.

25 My invention consists in the construction, combination and arrangement of the various parts of the device, whereby the objects contemplated are attained, as hereinafter more fully set forth, pointed out in my claims, and 30 illustrated in the accompanying drawings, in which;

Figure 1 shows a vertical, central, sectional view through a part of the manifold, having installed therein a vaporizer embodying my invention. Fig. 2 shows a plan elevation of the device detached from the manifold.

In the accompanying drawings I have used the reference numeral 20 to indicate 40 generally a part of the manifold of an internal combustion engine. Screwed into the wall of the manifold 20 is a body 4, having on its outer end upward and downward extensions 22 and 23. The body 4 is provided 45 with an opening 14 extending through it, the upper portion 15 of which is of greater diameter than the lower portion, so that the valve seat 16 is formed at the lower end of the larger portion 15. A plug 17 is screwed 50 into the lower end of the lower extension 23, and is provided with an opening extending through it which communicates with the opening 14. A fuel supply pipe 3 is extended into the plug 17. The pipe 3 connects 55 with the pipe 19, which is the main fuel

supply pipe communicating between the fuel tank and carbureter.

The inner end of the body 4 is provided with a cup shaped opening 24 in its upper surface. An opening 25 extends through 60 the body 4 from the cup shaped opening 24 to the opening 15, as shown.

The opening 25 extends through the body 4 from a point inside the manifold 20 to a point outside the manifold. 65

Screwed into the upper extension 22 is the stem 2 of the needle valve 7, which valve is adapted to coact with the seat 16 for closing the upper end of the smaller part of the passage 14. Secured to the stem 2 outside 70 the body 4, is a lever 1. Mounted on the lever 1 is an arm 27, which is insulated from the lever 21 by means of suitable material.

Mounted in the cup shaped opening is a nichrome wire 5, connected with which is 75 a suitable conducting wire 8. Extended through the opening 26 is suitable insulating material 28, in which is mounted the wire 8. The outer end of the wire 8 is connected at 10 with the lower end of the arm 80 27. Mounted on the body 4 outside the manifold is a block of insulating material 9. Mounted in the insulating block 9 is a conductor post 6, with which is connected the wire 29, adapted to be connected with 85 a suitable source of electrical energy.

Pivoted to the lever 1 is a suitable controlling lever 18.

The practical operation of my improved vaporizer will now be described. The vaporizer body is suitably installed in the manifold 20, and the pipe 19 is connected with the proper source of supply, and with the opening 14. The wire 29 is connected with the proper source of electrical energy. 95

It will be understood that the lever 18 extends through the dash of the driven vehicle when the device is used on the engine of such a vehicle. Otherwise the lever 18 may be dispensed with or connected up as desired. 100

When the lever 1 is swung to position where the arm 27 stands away from the post 6, the needle valve is closed. When it is desired to start the engine with heated fuel, the lever 1 is moved to position where the 105 arm 27 makes a contact with the post 6. At the same time the needle valve is opened, fuel is fed under pressure to the passage 14, the portion 15 thereof and the opening or passage 25 to the cup shaped opening 24, around 110

the nichrome wire 5. Contact being made as above mentioned, the current is established through the nichrome wire, which is heated to a red heat, thereby heating the fuel 5 directed around it from the passage 25. The nichrome wire 5 is connected with the body 4, and the current is therefore grounded on the body of the engine.

When the engine has been run for a short 10 time, my vaporizer may be moved to inoperative position by proper manipulation of the lever 1, and the fuel may be supplied to the carbureter in the regular way.

The advantage of such a device is readily 15 understood. The fuel necessary for starting the engine may be quickly and easily heated with a small supply of current, and the current may be turned off so that there is no waste after the engine has been started.

20 The vaporizer may be used as an auxiliary to the carbureter when the engine is under heavy load.

It will be seen from the foregoing description that the device is of comparatively 25 simple construction, and inexpensive to make.

One important feature of the construction 30 of my improved vaporizer lies in the arrangement of the cup 24, which opens on the side of the body 4 away from the direction from which the fuel comes during its ordinary passage through the manifold 20. Thus it will be seen that when the vaporizer 35 is moved to inoperative position and fuel is supplied to the manifold through the carbureter in the ordinary way, the wire 5 will be protected against the inrush of cold fuel from the carbureter by the walls of the cup 24, thereby avoiding as far as possible the 40 sudden cooling of the wire 5.

I appreciate that certain changes may be made in the construction and arrangement of the parts of my vaporizer, and the vaporizer shown in the drawings is simply an

exemplification of my device, and it is my intention to cover by this application any such changes which may be included in the scope of my claims. 45

I claim as my invention.

1. In a vaporizer, the combination of a 50 fuel passage, a body having a fuel opening extending through it, said body being adapted to be mounted in the wall of said fuel passage, with the ends of said opening on opposite sides of said wall, a cup formed at 55 the inner end of said opening, means controllable from the outside of the passage for supplying heat to the fuel in said cup, a valve for controlling said fuel opening, and means for simultaneously operating said 60 valve and said heat controlling means.

2. In a vaporizer, the combination of a 65 fuel passage, a body having a fuel opening extending through it, said body being adapted to be mounted in the wall of said fuel passage with the ends of said opening on opposite sides of the said wall, a cup formed at the inner end of said opening, and means provided from outside of said passage for 70 supplying heat to the fuel in said cup.

3. In a vaporizer, a body having a fuel opening extending through it, a cup formed at one end of said opening, a valve for controlling the opposite end of said opening, a lever on said valve, a contact arm in said lever, an insulating block on said body, a conductor post in said insulator, an electrical coil in said cup having one end connected with said body, and the other with the said contact arm, the said contact arm being 75 80 adapted to make contact with the said conductor post as the lever is moved to position upon the said valve.

Des Moines, Iowa, December 8, 1914.
JOHN A. THOMPSON.
